UNITED STATES PATENT OFFICE.

JAMES H. TEMPLE AND EVA M. TEMPLE, OF PORTLAND, OREGON.

ABDOMINAL SUPPORT.

1,250,048.

Specification of Letters Patent. Patented Dec. 11, 1917.

Application filed May 26, 1917. Serial No. 171,230.

To all whom it may concern:

Be it known that we, JAMES H. TEMPLE and EVA M. TEMPLE, citizens of the United States, residing at Portland, in the county 5 of Multnomah and State of Oregon, have invented certain new and useful Improvements in Abdominal Supports, of which the following is a specification.

Our invention relates to new and useful 10 improvements in abdominal supports and has for its primary object the provision of a support for use in the treatment of floating kidneys, prolapse conditions, hernia, obesity, and the like, and for use for obstetrical purposes, or as a support after abdominal operations of various classes.

In this connection our invention consists 20 of a main support or girdle formed in three parts, two constituting the back and side portions of the garment and the other the front portion, series of laces connecting the front or free edges of the former portion with the adjacent edges of the front portion so that the girdle as a whole may be drawn 25 as tightly as desired about the body of the patient. Both portions are stiffened vertically at suitable points by bones of whalebone, steel or other suitable material inserted in closed pockets formed in the girdle.

30 The invention further comprehends a secondary girdle or harness formed of relatively heavy webbing carrying at its front vertically disposed stiffening bones and being connected at its ends behind by laces.

35 A further object of our invention consists in the provision of a novel means for securing this secondary girdle or harness in the required adjusted position, said means including an adjustable connection between 40 the lower front portion of the girdle proper and the corresponding portion of the harness, whereby the front portion of the harness may be adjusted to engage about the patient at a higher or lower point, as desired, and further consisting in connecting 45 the rear free ends of the harness to the rear portion of the girdle by the same lace connecting the edges of the side and back portions of the girdle.

50 A still further object which we have in view is the provision of moisture absorbing thigh pads adapted to pass downwardly over the upper portions of the thighs and around the buttocks to properly hold the supporter 55 as a whole in place.

Still another object we have in view is the particular shaping of the parts forming the girdle so that together with the means for adjustment provided the girdle may be applied to bring desired pressure at all proper 60 points and to raise the abdomen and support it from the pubic arch bone upward.

With these and other objects in view, our invention will be more fully described, illustrated in the accompanying drawings and 65 then specifically pointed out in the claims which form a part of this application.

In the accompanying drawings:

Figure 1 illustrates the manner of applying our improved abdominal support. 70

Fig. 2 is a vertical sectional view taken centrally of the front portion of the supporting device.

Fig. 3 is a fragmentary sectional view of one of the thigh pads. 75

Fig. 4 is a fragmentary front elevation of the support.

Fig. 5 is a fragmentary rear elevation of the support.

The main girdle or body of our improved 80 abdominal support includes a pair of back and side forming portions 10 and a front portion 11 which in use are secured to each other by properly disposed lacings, as will be later explained. The front portion is 85 substantially rectangular in shape and of considerable length, being elongated at its lower end so that it may engage over the pubic arch bone. The side edges of the lower half of the front are practically 90 straight while the side edges of the upper half are shaped to conform to the contour of the abdomen. This portion 11 is formed of any suitable cloth of sufficient strength and is provided centrally with a stiffening strip 95 12 of heavy webbing or equivalent material which extends throughout the height of the front section, being secured thereto by stitches 13 and being formed to provide parallel pockets 14 which receive stiffening 100 bones 15 which are of less length than the front portion and which consequently may be adjusted vertically in the pockets to give the support less rigidity than would otherwise be the case. 105

The side and back portions 10 are formed preferably of the same material as the front portion and have their upper edges substantially straight so that the upper portion of the girdle will encircle the body of the 110

wearer at approximately the same height throughout its circumference, the only difference being that the front portion and adjacent parts of the side portions are somewhat higher. On the other hand, the lower edges of the portions 10 are inclined upwardly so that the free back ends of such portions are of considerably less height than their forward ends in order that the back edges of the portions 10 may lie above the patient's buttocks. Preferably each of the back and side portions 10 is formed by a relatively long front section 16, a short back section 17 and a gusset section 18, the gusset section being of considerably greater width at its lower than at its upper edge to give the proper curvature or fullness to the finished girdle, the sections being secured at their adjacent edges by stitching. Each of the gusset sections is provided medially with a vertically disposed strengthening strip 19 of webbing; which provides at its sides pockets 20 to receive stiffening bones 21 which extend throughout the entire length of the webbing. In like manner the rear ends of the sections 17 are provided with stiffening strips 22 which along their outer edges are formed with pockets 23 receiving bones 24 which extend throughout the length of the strips. A series of eyelets 25 is disposed at the free edge of each of the portions 10, being located immediately within the pockets 23 so that a lacing passed through the eyelets to draw the portions together at the back will pass about the stiffening bones and prevent any possibility of wrinkling or puckering of the edges of the garment through drawing up of the lacing. The front free edges of the portions 10 are provided with series of eyelets 26 and the side edges of the front portion 11 with corresponding series of eyelets 27. A pair of laces 28 and 29 are laced through the eyelets 26 and 27 at the forward end of one of the members 10 and adjacent end of the portion 11 so that they may be tied both at the upper and lower edge of the girdle, as indicated at 28'. Corresponding laces 29' and 30 are laced through the eyelets of the opposite side of the front portion 11 and at the edge of the adjacent side and back portion 10 and correspondingly knotted at the upper and lower edges of the girdle.

Straps 32 of heavy webbing or equivalent material are secured to the side portions of the lower edge of the front portion 11 of the girdle by stitching as indicated at 33 and at their opposite ends are adjustably secured in buckles 34 depending from tabs of webbing 35 secured to the outer face of the portions 10 at the point of juncture of the front sections 16 of such portions and the gusset sections 18. These strips of webbing are adapted to pass between the legs of the wearer and around and below the buttocks

and pads 36 are stitched to the inner faces of the strips 32 along those portions of such strips which pass between the legs. These pads are a great improvement as they will absorb all moisture and prevent chafing and 70 discomfort.

The method of applying this girdle or portion of the abdominal support thus far described will be readily apparent by reference to the drawings, particularly Figs. 1, 75 4 and 5, the absorbing thigh pads or strips 32 being adjusted to the proper length and the lacings 28 and 29, and 29' and 30 being drawn from their upper or lower ends or both to cause proper fitting of the front 80 portion and adjacent parts of the side and back portions about the body of the wearer. The girdle is tightened about the body of the wearer by a suitable lacing connecting the free ends of the portions 10, as will be 85 later explained.

The front portion at its sides is provided with flaps 37 which are stitched to its inner face just beyond the lines of the eyelets 27 and which lie between the body of 90 the patient and the adjacent parts of the girdle, the eyelets and laces when the girdle is in position, as will be apparent by reference to Fig. 5.

Coöperating with the above described girdle is a belt or harness including a pair of belt forming tapes 38 and 39 of heavy webbing or other suitable material which intermediate their length are connected to the upper and lower ends of a bracing strip or 95 element 40 in the form of a double thickness of webbing providing between them a pocket 41 to receive a stiffening bone 42. Each end of the belt forming strip or webbing 38 is secured to the adjacent end of the 100 strip 39 and the intermediate portion of the strip 39 is folded or twisted upon itself at its point of connection to the members 40, as shown at 42, so that while the belt section 38 will pass directly around the waist 110 of the wearer, the belt section 39 will have its intermediate portion projected downwardly in spaced relation to the portion 38 as clearly shown in Figs. 1 and 4 of the drawings. Bracing strips 43 of double webbing, corresponding to the members 40 and provided with pockets 44 to receive bones 45, are connected at their upper ends to the belt 38 adjacent the upper end of the strip 40 and at their lower ends to the belt 39 in 115 spaced relation to the lower end of the strip 40 so that while the strip 40 is vertically disposed the bracing strips 43 will diverge downwardly. A pair of transversely disposed eyelets 46 are located in the lower 120 end of the bracing strip 40 and serve to additionally secure the belt 39 thereto, and a lacing 47 is passed through these eyelets and through a corresponding pair of eyelets 48 in a tab 49 secured to the lower portion of 130

the front member 11 of the girdle and has its ends united as shown at 50 in order that the compound belt formed by the strips 38 and 39 may be held at any desired elevation 5 with respect to the lower edge of the girdle and may be kept from riding upward during use.

The joined ends of the strips 38 and 39 are each provided with a pair of eyelets 51 and a lacing 52 serves to adjustably draw the ends of the belts 38 and 39 toward each other and also to correspondingly draw the free rear edges of the girdle portions 10 toward each other. This is accomplished 15 by passing the intermediate portion of the lacing 52 outwardly through the upper eyelets 25 in the ends of the portions 10, lacing the ends of the lacing downwardly through the various eyelets to the 20 limit of the junctures of the belts 38 and 39, through the upper eyelets at said junctures back through the lower eyelets at said junctures, having elongated loops 53, continuing lacing the ends of the lacing through the 25 eyelets 25 of the portions 10 and knotting the ends of the lacing at the last eyelets as indicated at 54. Under these conditions, the portion of the lacing 52 joining the free edges of the girdle sections 10 and the portions 30 of the lacing joining the adjacent ends of the compound belt 38—39, may be loosened by utilizing the slack of the loops 53 so that the garment may be put on without removal of any of the lacings. By then 35 taking up this slack through pulling upon the loops the girdle proper may be drawn as tightly as desired and the compound belt may be also tightened correspondingly, after which the loops may be knotted as shown 40 at 55 in Fig. 5. Because of this it will be clear that both the girdle and compound belt will fit about the body of the wearer with the same snugness and absolute comfort is thereby assured. Obviously, by ad- 45 justment of the lacing 47 the forward portion of the compound belt may be raised or lowered and by varying the points at which the lacing 52 is looped off to the ends of the compound belt the back portion of this belt 50 may be raised or lowered.

From the foregoing description, taken in connection with the drawings, the manner of wearing and fitting the abdominal support will be readily understood and no description is necessary. It should be noted, however, that by making the moisture absorbing thigh pads and straps adjustable and by providing the girdle with two pairs of lacings connecting the front portion 11 with the side and back portions 10, a wide range of adjustment is permitted. Because of this either the lower or upper portions of the girdle may be tightened at will and the girdle made to properly conform to the 65 shape of the wearer. The compound belt

38—39 and particularly the bracing strips 40 and 43 constitute a pressure pad having great purchasing power due to its connection at its bottom to the front portion of the girdle and to the lacings passed through the 70 eyelets at the ends of the compound belt or pressure pad and through the ends of the back portions of the girdle.

Obviously, various minor changes in the shape of the various parts, as well as in 75 their proportions and the locations of the various bracing strips with their bone reinforcements, may be made to suit varying conditions without in the slightest degree departing from the spirit of our invention as set forth in the claims.

Having thus described the invention, what is claimed as new is:

1. An abdominal support including a girdle formed in sections adjustably connected by laces and adapted to encircle the waist and engage over the abdomen of the patient, a belt having an intermediate portion adapted to engage over the front of the girdle and end portions projecting 85 around toward the back of the girdle, the belt tapering in width from its intermediate portion to its ends, and a single lacing co-operating with the free ends of the girdle at the back and with the free ends of the 90 belt at the back for simultaneously and correspondingly tightening and securing both the girdle and belt.

2. An abdominal support including a girdle formed in sections adjustably connected by laces and adapted to encircle the waist and engage over the abdomen of the patient, a belt having an intermediate portion adapted to engage over the front of the girdle and end portions projecting around 100 toward the back of the girdle, the belt tapering in width from its intermediate portion to its ends, a single lacing co-operating with the free ends of the girdle at the back and with the free ends of the belt at the back for 105 simultaneously and correspondingly tightening and securing both the girdle and belt, vertically disposed stiffening elements located in the front of the girdle and adjustable vertically therein, and stiffening ele- 110 ments located in the front of the belt.

3. An abdominal support including a girdle formed in sections adjustably connected by laces and adapted to encircle the waist and engage over the abdomen of the patient, a belt having an intermediate portion adapted to engage over the front of the girdle and end portions projecting around toward the back of the girdle, the belt tapering in width from its intermediate 120 portion to its ends, a single lacing co-operating with the free ends of the girdle at the back and with the free ends of the belt at the back for simultaneously and correspondingly tightening and securing both 125 the girdle and belt.

the girdle and belt, vertically disposed stiffening elements located in the front of the girdle and adjustable vertically therein, stiffening elements located in the front of 5 the belt, certain of the stiffening elements of the belt being vertically disposed at the front thereof and others disposed at either side of the first and converging from the upper edge of the belt to the lower edge 10 thereof.

4. An abdominal support including a girdle shaped and proportioned to fit about the waist and over the abdomen of the patient and open at the back, a belt having 15 an intermediate portion adapted to engage over the front of the girdle and end portions projecting around toward the back of the girdle, the belt tapering in width from its intermediate portion to its ends and a common lacing closing the back of both the 20 girdle and belt.

5. An abdominal support including a girdle and belt both open at the back, the girdle being shaped to engage about the 25 waist and over the abdomen of a patient and the belt encircling the girdle, and a

common means for tightening and fastening both the girdle and belt.

6. An abdominal support including a girdle and belt both open at the back, the 30 girdle being shaped to engage about the waist and over the abdomen of a patient and the belt encircling the girdle, and a common means for tightening and fastening both the girdle and belt, said means causing 35 corresponding tightening of both the girdle and belt.

7. An abdominal support including a girdle and belt both open at the back, the 40 girdle being shaped to engage about the waist and over the abdomen of a patient and the belt encircling the girdle, the girdle tapering in width from its intermediate to its end portions, means for tightening and fastening both the girdle and belt, and adjustable means connecting the lower edge of 45 the front of the girdle with the lower edge of the front of the belt.

In testimony whereof we affix our signatures.

JAMES H. TEMPLE. [L. S.]
EVA M. TEMPLE. [L. S.]
